(57) **CLAIM**

The ornamental design for the wraparound peripheral grip for a game controller, as shown and described.

DESCRIPTION

FIG. 1 is a perspective view of a wraparound peripheral grip for a game controller;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a rear elevation view that shows the wraparound peripheral grip for a game controller in an unwrapped position.

The broken lines in the drawings illustrate portions of the wraparound peripheral grip for a game controller which form no part of the claimed design.
